DUPLEX LAPING MACHINE

Herbert S. Indge, Westboro, Mass., assignor to
Norton Company, Worcester, Mass., a corpora-
tion of Massachusetts

Application May 29, 1941, Serial No. 395,850

6 Claims. (CL 51—67)

The invention relates to lapping machines, and more particularly to a multiple spindle lapping machine for simultaneously lapping a plurality of cylindrical work pieces.

One object of the invention is to provide a simple and thoroughly practical lapping machine for cylindrical work pieces. Another object of the invention is to provide a multiple head machine whereby a plurality of cylindrical work pieces may be simultaneously lapped. Another object of the invention is to provide an automatically controlled machine for simultaneously lapping a plurality of cylindrical work pieces.

A further object of the invention is to provide a cylindrical lapping machine with a reciprocable type lapping element for lapping a cylindrical surface on a work piece for a predetermined time interval. Another object of the invention is to provide a lapping machine for simultaneously lapping a plurality of cylindrical work pieces which is semi-automatic in operation and each head of which is controlled by a single control lever.

Another object of the invention is to provide a multiple spindle cylindrical lapping machine in which a plurality of lapping heads are automatically moved toward and from a plurality of work pieces, lapping sticks on each of the heads are automatically started reciprocating as the head moves toward the work piece, and in which the work rotation is automatically initiated by the relative approaching movement of the lapping heads. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings in which is shown one of various possible embodiments of the mechanical features of this invention,

Fig. 1 is a front elevation of a lapping machine embodying the invention;

Fig. 2 is a left-hand end elevation of the lapping machine as shown in Fig. 1;

Fig. 3 is a diagrammatic showing of the hydraulic and electrical-control system;

Fig. 4 is a vertical sectional view, on an enlarged scale, through one of the work heads, showing the headstock and footstock spindles and centers;

Fig. 5 is a fragmentary vertical sectional view, taken approximately on the line 5—5 of Fig. 1, 55

showing the fluid motor for reciprocating the lapping sticks on one of the lapping heads;

Fig. 6 is a fragmentary front elevation, on an enlarged scale, of the lapping stick holder and its mounting;

Fig. 7 is a fragmentary sectional view, taken approximately on the line 7—7 of Fig. 6, showing the lapping sticks and holder in an operative position in engagement with a work piece; and

Fig. 8 is a fragmentary sectional view, on an enlarged scale, taken approximately on the line 8—8 of Fig. 4.

A lapping machine has been illustrated in the drawings, in which a machine base 10 is provided with an upper plane surface 11. A plurality of transversely extending T-shaped slots 12, 13, 14, 15, 16 and 17 are provided. A plurality of rotatable work supports are provided on the base 10, each work support comprising a headstock 20 and 20a and a footstock 21 and 21a. As illustrated in the drawings, two spaced rotatable work supports are provided but, if desired, the machine may be arranged to support any number of heads thereon, as is desired. The headstocks 20 and 20a are clamped in position on the surface 11 of the base 10 by means of a plurality of clamping bolts 22 and 22a. Two pairs of bolts are provided on each side of the headstock 20. The clamping bolts 22 and 22a pass through clearance apertures in the headstock 20 and the heads thereof are adjustably and slidably positioned within the T-shaped slots 12 and 13. It will be readily apparent from the foregoing disclosure that the headstock 20 may be transversely adjusted as desired.

The headstock 20 rotatably supports a spindle 25 in a pair of spaced anti-friction bearings 26 and 27. A multi-step V-groove pulley 28 is mounted on the outer end of the spindle 25. The pulley 28 is connected by a V-belt 29 with a pulley 30 mounted on a rotor shaft 31 of an electric motor 32. The electric motor 32 is mounted on a pivotally mounted supporting plate 33 which is pivotally connected by a rock shaft 34 with the headstock frame. An adjusting screw 35 (Fig. 1) is provided to facilitate pivotal adjustment of the plate 33 so that the center distance between the pulleys 28 and 32 may be adjusted to tension the driving belt 29 as desired.

The spindle 25 is a hollow spindle having a central bore 36 extending therethrough. At one end of the bore 36 is provided an internal frustoconical surface 37 which serves to support and locate a sleeve 38. The sleeve 38 may be held in position by means of a collar 39 which is screw

threaded onto the left-hand end of the sleeve 38 (Fig. 4). The sleeve 38 serves as a support for a work supporting center 40. The end of the sleeve 38 is enclosed by an end cap 41 which is provided with a clearance aperture 42 of sufficient size to receive the end portion of a work piece 43. A driving member, which in the present case comprises a single gear tooth 44, is adjustably positioned to engage one of the spaces between gear teeth on a gear or pinion 45 formed adjacent to the left-hand end of the work piece 43 (Fig. 4). A single tooth 44 serves as a driving element to rotate the work piece 43 during a lapping operation.

A footstock 21 is adjustably positioned on the surface 11 and is held in adjusted position thereon by clamping bolts 51 only one of which has been illustrated in Fig. 2. The footstock 21 comprises a footstock base 52 which serves as a support for a pivotally mounted frame 53. A stud 54 pivotally connects the frame 53 with the footstock base 52. The footstock frame 53 is provided with a rotatable spindle 55 which serves as a support for a footstock center 56 which in turn is arranged to engage and support the right-hand end of the work piece 43 (Fig. 4).

In order to facilitate loading of work pieces 43 into the machine, the footstock frame 53 is pivotally mounted so that it may be readily swung to and from an operative position by means of a manually operable lever 57. The lever 57 is fixedly mounted on a pivotally supported member 58 which is pivotally supported by a stud 59 on the footstock base 52. The pivotally mounted member 58 is connected by a stud 60 with one end of a link 61. The other end of the link 61 is pivotally connected by means of a stud 62 supported on the upper portion of the pivotally mounted footstock frame 53. The member 58 and the link 62 are arranged to serve as toggle levers whereby the pivotally mounted footstock frame 53 may be swung into engagement with an adjustable stop screw 63 and locked in an operative position for a lapping operation. After the lapping operation has been completed, the lever 57 may be readily rocked in a clockwise direction to break the toggle action and swing the pivotally mounted footstock frame 53 together with the footstock center 56 in a clockwise direction to an inoperative position so that the work piece 43 which has been lapped may be readily removed from the machine. Further details of construction of the footstock are not described herein since this footstock constitutes the subject matter of my copending U. S. patent application Serial No. 390,246 filed April 25, 1941.

The headstock 20a is identical in construction with the headstock 20, consequently the headstock 20a has not been illustrated in detail. In the various figures of the drawings, the same reference numerals suffixed with the letter *a* are used to designate corresponding parts in the headstock 20a. The headstock 20a is similarly adjustably clamped in position on the plane surface 11 of the machine by means of clamping bolts 22a the heads of which are arranged to slide within transversely extending T-slots 16 and 17 to facilitate a transverse adjustment of the headstock 20a.

A footstock 21a is provided having a footstock center 56a arranged to support the opposite end of a work piece supported by the headstock 20a. The footstock 21a is identical with the footstock 21, consequently this footstock will not be de-

scribed in detail. Like reference numerals apply to like parts suffixed with the letter *a*.

The base 10 also serves as a support for a vertically extending column 65. The column 65 has a lower plane surface which is supported by the upper plane surface 11 of the base 10. The column 65 is arranged to be clamped in adjusted position on the surface 11 by means of clamping bolts 66 and 67 (Fig. 1), the heads of which ride within the transversely extending T-slots 14 and 15. It will be readily apparent from the foregoing disclosure that the column 65 may be adjusted transversely relative to the base 10 and surface 11 to facilitate setting up the machine for a lapping operation. A horizontally extending arm 68 (Figs. 1 and 2) is formed integral with the column 65 and serves as a support for a pair of lapping heads 69 and 70. The arm 68 is provided with a substantially vertical plane surface 71 which serves as a supporting surface for brackets 72 and 73 of the lapping heads 69 and 70, respectively (Fig. 1). The arm 68 is provided with a pair of parallel horizontally arranged T-slots 74 and 75 by means of which the brackets 72 and 73 may be clamped in adjusted position on the arm 68. A plurality of clamping screws 76 and 77 are provided in the T-slots 74 and 75, respectively. The clamping bolts 76 and 77 pass through elongated slots in the bracket 72 and have their heads shaped to mate with the T-slots 74 and 75, respectively. It will be readily apparent from the foregoing disclosure that the bracket 72 may be readily adjusted longitudinally relative to the column 65 to facilitate adjustment of the lapping head 69 to position it in the desired relationship with a work piece 43 supported by the headstock 20 and footstock 21.

Similarly, the bracket 73 may be adjustably clamped in position on the arm 68 by means of a plurality of clamping screws 78 and 79 which pass through elongated slots in the bracket 73 and have their heads respectively mating with the T-slots 74 and 75. It will be readily apparent from the foregoing that by manipulation of the clamping bolts 78 and 79, the lapping head 70 may be adjusted longitudinally relative to the arm 68 to facilitate positioning the lapping head in the desired relationship with a work piece supported by the headstock 20a and footstock 21a.

In order to facilitate loading of work pieces into the machine and removal thereof after a lapping operation has been completed, it is desirable to provide a mechanism for raising and lowering the lapping heads 69 and 70 to and from an operative position. This is preferably accomplished by means of a fluid pressure mechanism such as, for example, an individual fluid pressure piston and cylinder associated with each of the lapping heads. A fluid pressure cylinder 80 is formed integral with the bracket 72. The side face of the cylinder 80 is provided with a dovetailed slideway (not shown) which mates with a correspondingly shaped dovetailed slideway 81 formed on the lapping head 69. A piston 82 is slidably mounted in the cylinder 80 and is connected to one end of a piston rod 83. The upper end of the piston rod 83 is connected to a plate 84 mounted on the upper end of the lapping head 69 (Fig. 3). The raising and lowering of the lapping head 69 is accomplished by passing fluid under pressure either through a pipe 85 into a cylinder chamber 86 below the piston 82 to raise the piston 82 and the lapping head 69, or passing fluid under pressure through a pipe

87 into a cylinder chamber above the piston 82 to cause a downward movement of the lapping head 69 into an operative position. The raising and lowering mechanism for the lapping head 70 is identical with the mechanism for raising and lowering the head 69, consequently this mechanism is not illustrated and described in detail. Like parts are indicated by like reference numerals suffixed with the letter *a*.

A fluid pressure system is provided to supply fluid under pressure to raise and lower the lapping heads 69 and 70 as desired. This system may comprise a reservoir 90, preferably located within the base 10 of the machine. Fluid under pressure is drawn from the reservoir 90 by a motor driven pump 91 through a pipe 92 and is forced under pressure through a pipe 93 to a control valve 94. A variable pressure relief valve 95 is connected in the pipe line 93 whereby excess fluid under pressure in the system may be returned directly to the reservoir 90, thus maintaining a desired and predetermined pressure in the system.

The control valve 94 is a piston type valve comprising a valve stem 96 having valve pistons 97 and 98 formed integrally therewith. In the position of the valve (Fig. 3), fluid under pressure passing through the pipe 93 enters a valve chamber located between the valve pistons 97 and 98 and passes out through the pipe 85 into the cylinder chamber 80 to move the piston 82 upwardly to raise the lapping head 69 and maintain it in an inoperative position during a loading operation. During this movement, fluid in the upper chamber of the cylinder 80 exhausts through the pipe 87, through a valve chamber located between the valve piston 97 and an end cap 99 on the end of the valve 94, and exhausts through a pipe 100 into the reservoir 90. A pair of electric solenoids 103 and 104 are provided for shifting the valve stem 96 either toward the left or toward the right, depending upon which solenoid is energized. When it is desired to move the lapping head 69 into an operative position for a lapping operation, the solenoid 103 is energized in a manner to be hereinafter described to shift the valve stem 96 toward the left (Fig. 3), thus shifting the valve pistons 97 and 98 so that fluid under pressure in the pipe 93 entering the chamber located between the valve pistons 97 and 98 passes upwardly through the pipe 87 into the upper cylinder chamber in the cylinder 80 to cause a downward movement of the piston 82 and the lapping head 69 to position it in an operative position for a lapping operation.

During the downward movement of the piston 82 and the lapping head 69, fluid within the cylinder chamber 80 is exhausted through the pipe 85 into a valve chamber located between the valve piston 98 and an end cap 101 fastened on the right-hand end of the valve 94 (Fig. 3). Fluid under pressure in this chamber exhausts through a pipe 102 into the reservoir 90.

A similar control valve 94a is provided for controlling the admission to and exhaust of fluid from the cylinder 80a so as to control the movement of the lapping head 70 to and from an operative position. The control valve 94a is identical with the control valve 94, consequently this valve will not be described in detail. Corresponding parts will be designated by the same reference numeral suffixed with the letter *a*.

The lapping heads, as illustrated in the drawings, are arranged so that two spaced cylindrical portions 105 and 106 of the work piece 43 may

be simultaneously lapped to the desired and predetermined extent. A lapping stick holder 107 is provided for supporting two pairs of spaced bonded abrasive lapping sticks 108 and 109 (Fig. 6) for lapping each of the portions 105 and 106, respectively. The lapping stick holder 107 is pivotally supported by a pair of oppositely extending trunnions 110 and 111 which are in turn supported by a pair of downwardly extending arms 112 and 113. The arms 112 and 113 are fixedly supported at the lower end of a pivotally mounted member 114. The member 114 is pivotally supported by a stud 115 which is free to slide vertically relative to the head 69. A roller 116 is supported by a stud 117 (Fig. 5) adjacent to the upper end of the member 114 and is maintained in operative engagement with a cam 118 by means of a tension spring 119. The cam and roller are provided so that when the member 114 is oscillated, the cam will produce a slight vertical movement of the pivotally supported member 114 so that a straight-line reciprocatory movement is imparted to the lapping sticks 108 and 109 to facilitate a uniform engagement of the lapping elements with the periphery of the work piece during their entire reciprocating stroke.

A suitable power operated mechanism is provided for oscillating the member 114 to reciprocate the lapping sticks 108 and 109 in operative engagement with the spaced portions 105 and 106 of the work piece 43. In the preferred form a self-contained fluid motor 120 is provided comprising a cylinder 121 (Fig. 5) having a piston 122 slidably mounted therein. The piston 122 is connected by means of a piston rod 123 with the upper end of the oscillatable member 114. A pilot valve 124 is slidably mounted within the casing of the motor 120. The pilot valve 124 is provided with a central bore or aperture which contains a slidably mounted shuttle type reversing valve 125. The pilot valve 124 is provided with a pair of adjustable collars 126 and 127 which are engaged by an upwardly extending portion of the oscillatable member 114 by means of which the pilot valve 124 is automatically shifted at the end of the stroke to shift the reversing valve 125 and thereby change the direction of oscillation of the member 114 continuously to reciprocate the lapping sticks 108 and 109.

Fluid under pressure is admitted through a pipe 128 into the valve mechanism to actuate the piston 122 as desired. An exhaust pipe 129 is provided whereby fluid may readily be exhausted from the motor 120 into the reservoir 90.

The collars 126 and 127 are preferably adjustably mounted on the valve stem so that the length of the reciprocatory stroke of the oscillatable member and also the reciprocatory stroke of the lapping sticks 108 and 109 may be adjusted as desired. This hydraulic motor 120 has not been described in detail in the present application, since the details of the motor are not considered to be a part of the present invention. Any standard motor, either hydraulic or otherwise, might be employed for this purpose. For details of disclosure not contained herein, reference may be had to the prior U. S. Patent 2,212,871 to Wallace H. Wood dated August 27, 1940.

The lapping head 70 is similarly constructed and consequently has not been illustrated in detail. The parts illustrated, however, are identified by the same reference numerals suffixed by the letter *a*. The lapping arm 70 is provided

with a similar fluid motor 120a (Fig. 3) for imparting a reciprocatory movement to the lapping sticks 108 and 109.

It is desirable automatically to start the reciprocatory movement of the lapping sticks 108 and 109 when the lapping head 69 is moved toward an operative position and similarly to stop the reciprocation thereof when the lapping head is moved to an inoperative position. To accomplish this desired result, normally closed valves 130 and 130a are provided for controlling the fluid motors 120 and 120a, respectively. The valves 130 and 130a may be opened by means of pivotally mounted levers 131 and 131a, respectively, each having a roller 132 and 132a, respectively. In order that the valves 130 and 130a may be automatically controlled by the approaching and receding movement of the lapping heads 69 and 70, respectively, a pair of cams 133 and 133a are adjustably mounted on the brackets 72 and 73, respectively. The cams 133 and 133a are arranged to be engaged by the rollers 132 and 132a, respectively, when the heads are moved downwardly toward an operative position to swing the levers 131 and 131a in a clockwise direction to open the valves 130 and 130a and thereby automatically to start the reciprocatory movement of the lapping sticks 108 and 109 as they move into operative engagement with the work piece to be lapped.

In order that the cycle of operation of the machine may be automatic, it is desirable to provide an automatically actuated mechanism for starting the rotation of the work drive motor 32 in timed relationship with the other parts of the machine. In the preferred form, it is desirable to start the rotation of the motor 32 when the lapping head 69 is moved toward an operative position and similarly to stop the work drive motor when the head is moved to an operative or loading position. A rock shaft 135 is supported by the bracket 72. The rock shaft 135 is provided with an adjustable arm 136, the lower end of which is provided with an actuating roller 137. The roller 137 is arranged in the path of a cam 138 which is adjustably mounted on the vertically movable lapping head 69. An arm 139 is also mounted on the rock shaft 135 and is connected by means of a link 140 to actuate a normally open limit switch 141 when the lapping head is moved toward an operative position. When the cam 138 operates to close the limit switch 141, it serves to close a magnetic starter switch 142 which receives its power from any suitable source, such as indicated by the power lines 143, to start the work driving motor 32.

Similarly, a rock shaft 135a (Fig. 3) is mounted on the bracket 73 and is provided with an adjustably mounted arm 136a having a roller 137a arranged in the path of a cam 138a. The cam 138a is adjustably carried by the vertically movable lapping head 70. An arm 139a is also carried by the shaft 135a and is arranged so that when the cam 138a moves downwardly, it rocks the arm 136a, the shaft 135a, and the arm 139a to close a normally open limit switch 141a which is in turn connected to close a magnetic starter switch 142a to start the work drive motor 32a for a lapping operation.

A relatively high voltage circuit is utilized through the magnetic starter switches 142 and 142a to drive the work driving motors 32 and 32a. A pair of transformers 150 and 150a are

provided for stepping down the current for the remaining control apparatus on the machine.

A push button starting switch 151 is connected in series with a normally open limit switch 152 which in turn is connected with the solenoid 103. The switch 152 is arranged so that the valve 94 cannot be shifted to move the lapping head 69 downwardly until the footstock frame 53 is swung into operative supporting engagement with the work piece 43. An adjustable electric time delay relay 153 is connected in the circuit and arranged so that it is set in motion when the switch 141 closes on the downward movement of the lapping head 69 toward an operative position. The electric time relay 153 may be any of the standard well known time relays such as, for example, the well known relay known as the "Microflex" relay manufactured by the Eagle Signal Corporation of Moline, Illinois. The time relay 153 is connected to control the duration of the lapping operation. After a predetermined time interval has elapsed, the time relay 153 operates to deenergize the solenoid 103 and energize the solenoid 104 which in turn shifts the valve stem 96 into the position illustrated in Fig. 3 so as to admit fluid under pressure to raise the lapping head 69 to an inoperative position, thus terminating the lapping operation.

A similar push button switch 151a is provided which is connected in series with a normally open limit switch 152a. The limit switch 152a is in turn connected with the solenoid 103a and is arranged so that the push button switch 151a cannot start an approaching movement of the lapping head 70 until the footstock frame 53a is moved into an operative supporting engagement with the work piece to be lapped. An electrical time relay 153a is operatively connected so that when the limit switch 141a is closed during the downward movement of the lapping head 70 toward an operative position, it serves to govern the extent of the lapping cycle. After a predetermined time interval has elapsed, the time relay operates to deenergize the solenoid 103a and to energize the solenoid 104a which shifts the valve 94a into the position shown in Fig. 3 to terminate the lapping operation by admitting fluid under pressure to move the lapping head 70 upwardly to an inoperative position.

A pair of stop switches 154 and 154a are provided to facilitate stopping the lapping cycle at any time during a lapping operation on either head of the machine. When the push button switches 154 and 154a are closed, these switches serve immediately to energize the solenoids 104 or 104a, respectively, to shift the valves and thus raise the heads 69 or 70 upwardly to an inoperative position, thus terminating the lapping operation, in case it is desired or necessary to start the lapping operation before the normal cycle has been completed.

The operation of this machine will be readily apparent from the foregoing disclosure. Assuming the various mechanisms of the machine to have been previously adjusted, a work piece 43 is positioned on the headstock center with the driving tooth 44 engaging a gear space of the gear 45 of the work piece 43, after which the footstock control lever 57 is moved to swing the footstock frame 53 or 53a into operative supporting engagement with the center 56 engaging and supporting the footstock end of the work piece. This movement of the footstock to an operative position closes the safety interlock switch 152 so that when the operator desires to

stop the lapping cycle, it is merely necessary to close the push button switch 151 to energize the solenoid 103, thus shifting the valve 94 so that fluid under pressure is admitted to the pipe 87 to cause a downward movement of the piston 82 and the lapping head 69 to move the abrasive lapping sticks 108 and 109 into operative engagement with the spaced portions 105 and 106 of the work piece 43 to lap the same.

During the downward movement of the lapping head 69, the roller 132 engages the cam 133 after which continued movement rocks the valve control lever 131 to open the valve 130 and thereby start the fluid motor 120, thus starting the reciprocation of the lapping sticks 108 and 109. The downward movement of the lapping head 69 also serves to move the cam 138 into engagement with the actuating roller 137, after which continued movement serves through the arm 136, the rock shaft 135, and the arm 139 to close the normally open limit switch 141. The closing of the limit switch 141 serves to close the magnetic starter switch 142 to start the work drive motor 32, thus starting rotation of the work piece 43. At the same time, the closing of the switch 141 serves to set in motion the time delay relay 153 which allows the lapping operation to proceed for a definite and predetermined time interval, after which the relay trips and energizes the solenoid 104 to again shift the control valve 94 into the position of the parts shown in Fig. 3 to admit fluid under pressure through the pipe 85 into the cylinder chamber 86 to cause an upward movement of the piston 82 and the lapping head 69, thus terminating the lapping operation. During the upward movement of the lapping head 69, the roller 132 rides up the cam face 133 and allows the lever 131 to swing in a counterclockwise direction to close the valve 130, thus stopping the flow of fluid to stop the fluid motor 120, thus terminating the reciprocation of the lapping sticks 108 and 109.

Similarly, a work piece may be mounted on the headstock center 40a and the footstock frame 53a may then be swung into operative supporting engagement with the center 56a in engagement with the work to support the same for a lapping operation. The operation of this second lapping head unit is identical with the one just previously described, consequently it is not deemed to be necessary to describe in detail the operation of the second work supporting and lapping unit. While this machine has been illustrated with two work supporting and lapping units, it will be readily apparent that a plurality of units, any number desired, might be arranged on a single machine whereby one operator might simultaneously operate and control a plurality of lapping operations at the same time.

During the downward movement of the lapping head 69, the roller 132 engages the cam 133, after which continued movement rocks the valve control lever 131 to open the valve 130, thereby to start the fluid motor 120 and thus starting the reciprocation of the lapping sticks 108 and 109. The downward movement of the lapping head 69 also serves to move the cam 138 into engagement with the actuating roller 137 after which continued movement serves through the arm 136, the rock shaft 135, and the arm 139 to close the normally open limit switch 141. The closing of the limit switch 141 serves to close the magnetic starter switch 142 to start the work drive motor 32, thus starting rotation of the work piece 43. At the same time, the closing of the switch 141

serves to set in motion the time delay relay 153 which allows the lapping operation to proceed for a definite and predetermined time interval, after which the relay trips and energizes the solenoid 104 again to shift the control valve 94 into the position of the parts shown in Fig. 3 to admit fluid under pressure through the pipe 85 into the cylinder chamber 86 to cause an upward movement of the piston 82 and the lapping head 69, thus terminating the lapping operation. During the upward movement of the lapping head 69, the roller 132 rides up the cam face 133 and allows the lever 131 to swing in a counterclockwise direction to close the valve 130, thus stopping the flow of fluid to stop the fluid motor 120, thus terminating the reciprocation of the lapping sticks 108 and 109.

Similarly, a work piece may be mounted on the headstock center 40a and the footstock frame 53a may then be swung into operative supporting engagement with the center 56a in engagement with the work to support the same for a lapping operation. The operation of this second lapping head unit is identical with the one previously described, consequently it is not deemed necessary to describe in detail the operation of the second work supporting and lapping unit. While this machine has been illustrated with two work supporting and lapping units, it will be readily apparent that a plurality of units, any number desired, might be arranged on a single machine, whereby one operator might simultaneously operate and control a plurality of lapping operations at the same time.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a lapping machine having a rotatable work support including a headstock and a footstock, a rotatable spindle on said headstock, an electric motor to rotate said spindle, means to move said footstock to and from an operative position, a lapping head including a reciprocable lapping stick, means to reciprocate said stick, means including a piston and cylinder to move said head and stick to and from an operative position, an electrically actuated control valve to control the admission to and exhaust of fluid from said cylinder, and an electrical interlock between said footstock and control valve including a switch actuated by movement of the footstock to an operative position to actuate said control valve to cause a movement of the lapping head toward an operative position only when the footstock is in an operative position.

2. In a lapping machine having a rotatable work support including a headstock and a footstock, a rotatable headstock spindle supported on said headstock, an electric motor to rotate said spindle, means including a manually operable toggle lever mechanism to swing said footstock to and from an operative position, a lapping head including a reciprocable lapping stick, a fluid motor on said head to reciprocate said stick, a fluid operated piston and cylinder to move said head and stick to and from an operative position,

a solenoid actuated control valve to control the passage of fluid under pressure to and from said cylinder, and an electrical interlock between said footstock and control valve including a limit switch which is actuated by movement of the footstock to an operative position to facilitate actuation of the control valve to cause a movement of the lapping head toward an operative position only when the footstock is in an operative position.

3. In a lapping machine having a rotatable work support including a headstock and a pivotally mounted footstock, work supporting centers thereon, a rotatable spindle carried by said headstock and supporting said headstock center, an electric motor to rotate said spindle, means including a manually operable toggle lever mechanism to swing said footstock to and from an operative position, a lapping head including a reciprocable lapping stock, a fluid motor on said head to reciprocate said stock, a fluid operated piston and cylinder to move said head and stock to and from an operative position, a solenoid actuated control valve to control the passage of fluid under pressure to and from said cylinder, an electrical interlock between the footstock and control valve including a switch actuated by movement of the footstock to an operative position to facilitate actuation of the control valve to cause a movement of the lapping head to an operative position only when the footstock is in an operative position, a normally open limit switch actuated by movement of said head to an operative position, and an electrical time delay relay set in motion by said switch to control the extent of the lapping operation.

4. In a lapping machine having a rotatable work support including a headstock and a pivotally mounted footstock, work supporting centers thereon, a rotatable spindle carried by said headstock and supporting said headstock center, an electric motor to rotate said spindle, means including a manually operable toggle lever mechanism to swing said footstock to and from an operative position, a lapping head including a reciprocable lapping stick, a fluid motor on said head to reciprocate said stick, a fluid operated piston and cylinder to move said head and stick to and from an operative position, a solenoid actuated control valve to control the passage of fluid under pressure to and from said cylinder, an electrical interlock between the footstock and control valve including a limit switch actuated by movement of the footstock to an operative position to facilitate actuation of the control valve to cause a movement of the lapping head to an operative position only when the footstock is in an operative position, a normally open limit switch actuated by movement of said head to an operative position, an electrical time delay relay

set in motion by said switch to control the extent of the lapping operation, a magnetic starter switch which is controlled by said limit switch to start the electric motor when the lapping head moves into an operative position, and a solenoid energized by said time delay to shift the control valve to move the lapping head to an inoperative position.

5. In a lapping machine having a rotatable work support including a headstock and a pivotally mounted footstock, work supporting centers thereon, a rotatable spindle carried by said headstock and supporting said headstock center, an electric motor to rotate said spindle, means including a manually operable toggle lever mechanism to swing said footstock to and from an operative position, a lapping head including a reciprocable lapping stick, a fluid motor on said head to reciprocate said stick, a fluid operated piston and cylinder to move said head and stick to and from an operative position, a valve to control the passage of fluid under pressure to and from said cylinder, a solenoid to shift said valve including a limit switch actuated by movement of the footstock to an operative position so as to move said lapping head toward an operative position, an electrical interlock between the footstock and control valve to facilitate actuation of the control valve to cause a movement of the lapping head to an operative position only when the footstock is in an operative position, a normally open limit switch actuated by movement of said head to an operative position, and an electrical time delay relay set in motion by said switch to control the extent of the lapping operation.

6. In a lapping machine having a rotatable work support including a headstock and a pivotally mounted footstock, work supporting centers thereon, a rotatable spindle on said headstock, means including an electric motor to rotate said spindle, manually operable means to move said footstock to and from an operative position, a lapping head including a reciprocable lapping element, means to reciprocate said element, means including a piston and cylinder to move said head to and from an operative position, a control valve to control the passage of fluid under pressure to and from said cylinder, an electrical solenoid to shift said valve to move said head to an operative position, an electrical time delay relay which is set in motion by the approaching movement of said head to control the duration of the lapping operation, and a second solenoid which is energized by said relay after a predetermined time interval has elapsed to shift said valve to move said lapping head to an inoperative position.

HERBERT S. INDGE.

CERTIFICATE OF CORRECTION.

Patent No. 2,311,185.

February 16, 1943.

HERBERT S. INDGE.

It is hereby certified that error appears in the printed specification of the above numbered patent requiring correction as follows: Page 6, second column, lines 24 and 25, strike out the words "including a limit switch actuated by movement of the footstock to an operative position" and insert the same after "valve" in line 28; and that the said Letters Patent should be read with this correction therein that the same may conform to the record of the case in the Patent Office.

Signed and sealed this 6th day of April, A. D. 1943.

Henry Van Arsdale,

(Seal)

Acting Commissioner of Patents.
